D 014,000

DESIGN FOR A COMB AND BRUSH BOX.

Design No. 14,000, dated June 26, 1883.

UNITED STATES PATENT OFFICE.

HART O. BERG, OF NEW YORK, N. Y

DESIGN FOR A COMB AND BRUSH BOX.

SPECIFICATION forming part of Design No. 14,000, dated June 26, 1883.

Application filed May 5, 1883. Term of patent 3½ years.

To all whom it may concern:

Be it known that I, HART O. BERG, a citizen of the United States, and a resident of New York, in the city and county of New York, have invented and produced a new and original 5 Design for a Brush and Comb Box, of which the following is a specification, reference being had to the accompanying photographic representation, forming a part thereof, said 10 photograph containing two views of the box, of which—

Figure 1 is a perspective view of the box closed, and Fig. 2 is a view of it when opened.

My design relates to a new, useful, and original 15 configuration of a comb and brush box; and it consists in making that portion of the box in which the head of the brush is placed square-shaped, and allowing one end of the

box to slope off abruptly into an extension having a circumferential configuration like 20 that of the handle of the brush.

By referring to the photograph my design will be more clearly understood. A is the square-shaped portion of the box, which may be made as above indicated, and B is the extension of the same, having the circumferential configuration as described.

What I claim as new, and desire to secure by Letters Patent, is—

The design for a brush and comb box, substantially herein shown and described.

HART O. BERG.

Witnesses:

JOSEPH L. BERG,
FRANCIS FICKE.
